US00D868953S

(12) United States Design Patent (10) Patent No.: US D868,953 S
McKendree (45) Date of Patent: * Dec. 3, 2019

(54) WAX ARTICLE

(71) Applicant: The Procter & Gamble Company,
Cincinnati, OH (US)

(72) Inventor: Justin Thomas McKendree, Hardin,
KY (US)

(73) Assignee: The Procter & Gamble Company,
Cincinnati, OH (US)

() Term: 15 Years

(21) Appl. No.: 29/636,395

(22) Filed: Feb. 8, 2018

(51) LOC (12) Cl. 23-04

(52) U.S. Cl.

USPC D23/366; D23/367; D28/8.2

(58) Field of Classification Search

USPC D23/208, 355-369; D14/209.1, 212-213;
D8/1, 391
CPC A61L 9/02; A61L 9/03; A61L 9/12; A61L
9/035; A61L 9/125; A61L 2209/15; A61L
